DRILL PIPE FLOAT VALVE

Henry G. Osburn, Oklahoma City, Okla.

Application October 18, 1951, Serial No. 251,887

3 Claims. (Cl. 255—28)

This invention relates to float valves of the type used in the drill pipe of oil, water, or gas well rotary drilling mechanisms.

As it is well known, oil wells and the like are usually drilled by the rotary method, wherein a drilling bit is secured to the lower end of a plurality of joints of drill pipe which are in turn secured in tandem relation. During the drilling operation, the drill pipe is rotated by suitable equipment located on the surface of the earth to rotate the drill bit and break up and displace the earth strata. As the drill bit is moved downwardly, the well bore is formed. To remove the cuttings from the well bore which are made by the drill bit, fluid is forced downwardly through the drill pipe and drill bit. The drilling fluid is constrained to discharge from the well bore upwardly through the annulus surrounding the drill pipe, and in doing so, carries the earth and rock cuttings to the surface of the well for disposal.

When the well gets deep, the drill pipe gets longer and heavier and is difficult to support from the surface of the well, particularly when removing or inserting the drill pipe in the well bore for repairs. To alleviate this condition, there have been devised various types of float valves adapted to be interposed in the drill string or pipe. These float valves open downwardly to permit the normal flow of the drilling fluid, but preclude a retrograde or upward flow of fluid through the drill pipe. Therefore, when the normal flow of drilling fluid is stopped, the drill pipe will float in the drilling fluid remaining in the well bore. Thus the drill pipe may be floated in or out of a well bore to reduce the exertion of tension on the drill pipe and reduce the power required to install or remove the drill pipe.

The drilling fluid utilized in the drilling of substantially all wells is very abrasive; and when the fluid is caused to flow in a turbulent manner, the drill pipe and couplings used therewith are quickly worn away. All of the float valves heretofore used, to the best of applicant's knowledge, cause a turbulent flow of the drilling fluid sometime prior to the entrance of the fluid into the drill bit in such a manner that the drill pipe or couplings disposed below the valve are unduly worn. Furthermore, the float valve bodies are not sealed to the member in which they are disposed, thereby causing a wash out of the member as well as the valve and rendering the valve useless.

The present invention contemplates a novel float valve preferably installed in the drill collar connecting the lowermost joint of drill pipe to the drill bit. In the use of my valve, as the drilling fluid is discharged from the valve body, it immediately enters the drill bit to preclude a wash out or wearing away of the drill collar. Furthermore, the valve body is efficiently sealed to the drill collar and has an internal diameter substantially equal to the fluid passageway through the drill collar, thereby providing a smooth flow of fluid through the valve and a smooth flow of fluid into the valve. In this manner, the drill collar may remain in service the

maximum length of time before being discarded or remachined.

An important object of this invention is to reduce the number of wash outs of drill collars and the like to a minimum.

Another object of this invention is to increase the efficiency of the rotary method of drilling.

Another object of this invention is to provide a float valve having a long service life and which will not plug the fluid passageway in the event the valve stem becomes broken.

A further object of this invention is to provide a float valve having a solid wall tubular body.

A still further object of this invention is to provide an efficient float valve which may be economically manufactured.

Other objects and advantages of the invention will be evident from the following detailed description, read in conjunction with the accompanying drawings, which illustrate my invention.

In the drawings:

Figure 1 is an elevational view of a novel float valve installed in a drill collar.

Figure 2 is an enlarged sectional view of the float valve and a portion of the drill collar shown in Fig. 1.

Referring to the drawings in detail and particularly Fig. 1; reference character 2 designates a drill collar utilized to interconnect a drill bit 4 to lower end of a string of drill pipe (not shown) and to increase the weight applied on the bit 4 as it is well known in the art. A fluid passageway 6 is provided in the drill collar 2 to conduct the drilling fluid from the drill pipe to the drill bit 4. The fluid passageway 6 communicates at its lower end with a counter-bore 8, which in turn communicates with a tapered and threaded bore 10. The threaded bore 10 receives the threaded shank 12 of the drill bit 4.

A novel float valve generally indicated at 14 is disposed in the counter-bore 8 and is shown in detail in Fig. 2. The float valve 14 comprises a solid wall tubular body or housing 16 of a length slightly less than the length of the counter-bore 8 of the drill collar 2. A plurality of radially disposed webs 18 extend inwardly from the inner periphery of the body 16 and are joined at their inner ends to form a ring-like guide 20. An apertured valve guide 22 is disposed on the guide 20 and has an outwardly extending circumferential flange 24 on the central portion thereof. The flange 24 limits the downward movement of the valve guide 22 in the ring 20 for purposes as will be hereinafter set forth.

A valve stem 26 is reciprocally disposed in the valve guide 22 and has a conical shaped valve head 28 on the upper end thereof. The valve head 28 is adapted to be moved vertically in the valve body 16 to alternately permit and preclude the flow of drilling fluid through the valve body. A counter-bore 30 is provided in the lower end of the valve head 28 to receive the upper end of a helical spring 32. The spring 32 extends downwardly around the valve stem 26 and valve guide 22 and is anchored at its lower end on the flange 24. It will be apparent that the spring 32 constantly tends to move the valve head 28 and stem 26 upwardly into a closed position.

A tapered area 34 is provided on the outer surface of the valve head 28 and is adapted to contact the tapered area 36 of a valve seat 38. The valve seat 38 is inserted in the upper end 40 of the tubular valve body 16 and contacts a circumferential shoulder 42 provided on the inner periphery of the body 16. The valve seat 38 is preferably of a size to fit tightly in the valve body 16. In addition, a set screw 44 is provided in the wall of the body 16 in contact with the valve seat 38 to further secure the seat

38 in position. A circumferential groove 46 is provided in the outer surface of the valve head 28 adjacent the lower end of the tapered area 34 to receive a sealing ring 48. The sealing ring 48 is adapted to contact the tapered area 36 of the valve seat 38 to assure an efficient sealing of the valve head 28 on the seat 38.

The inner diameter of the valve seat 38, at the upper end thereof, is preferably substantially equal to the diameter of the fluid passageway 6 of the drill collar 2 to enhance a smooth flow of the drilling fluid into the valve body 16. A circumferential groove 50 is provided in the outer surface of the valve seat 38 in communication with the upper end thereof and a mating groove 52 is provided in the inner periphery of the valve body 16 in communication with the upper end 40 thereof. The grooves 50 and 52 receive an end sealing ring 54. In addition, a circumferential groove 56 is provided in the outer surface of the valve body 16 adjacent the upper end 40 thereof to receive a side sealing ring 58. The sealing ring 58 contacts the walls of the counter-bore 8 and the sealing ring 54 contacts the shoulder 60 formed between the bore 6 and the counter-bore 8 to preclude the outward flow of drilling fluid around the outer surface of the valve body 16 into contact with the walls of the counter-bore 8. Thus, the abrasive drilling fluid is precluded from washing out the drill collar 2 at the upper portion of the counter-bore 8.

The lower end 62 of the valve body 16 is tapered inwardly to provide an inner diameter substantially equal to the diameter of the fluid passageway 64 extending through the drill bit shank 12. A circumferential groove 66 is provided in the lower end face 68 of the valve body 16 to receive another end sealing ring 70. Furthermore, a circumferential groove 72 is provided in the outer surface of the valve body 16 adjacent the lower end face 68 to receive another side sealing ring 74. The sealing ring 70 contacts the upper end of the drill bit shank 12 and the sealing ring 74 contacts the walls of the counter-bore 8 to preclude an outward flow of the abrasive drilling fluid and a wash out of the extreme lower end of the drill collar 2.

Operation

When installing the float valve 14, the drill bit 4 is simply removed and the float valve 14 is inserted in the counter-bore 8 through the lower end of the drill collar 2. Upon reassembly of the drill bit 4 in the lower end of the drill collar 2, the upper end of the shank 12 contacts the lower end sealing ring 70 to force the float valve 14 into position in the counter-bore 8. When the drill bit 4 is in operating position, as illustrated in both Figs. 1 and 2, the upper end of the shank 12 will have moved the float valve 14 into such a position that the lower end sealing ring 70 will be in sealing contact with the upper end of the shank 12 and the upper sealing ring 54 will be in sealing contact with the shoulder 60.

During operation of the drill bit 4, drilling fluid is forced under pressure downwardly through the drill pipe and passageway 6 of the drill collar 2 into the upper end of the valve body 16. The drilling fluid will force the valve head 28 and valve stem 26 downwardly against the action of the helical spring 32. It will be apparent that when the valve head 28 has been moved downwardly from the position shown in Fig. 2, the drilling fluid will circulate around the valve head 28 and through the valve body 16 into the fluid passageway 64 of the drill bit shank 12. The drill bit 4 is provided with various fluid passageways (not shown) communicating with the passageway 64 to discharge the drilling fluid into the lower end of the well bore (not shown).

Since the inner diameter of the valve seat 38 is substantially equal to the fluid passageway 6, and the inner diameter of the valve body 16 at the lower end 62 thereof is substantially equal to the fluid passageway 64, the minimum of turbulence will be provided in the flow of the

drilling fluid while passing through the float valve 14. It is also to be noted that once the drilling fluid enters the float valve 14, it does not thereafter again contact the drill collar 2. Therefore, the abrasive drilling fluid will not cause a wash out of the drill collar 2 and hence the expensive and time consuming machining operations necessarily required as a result of such wash outs will also be reduced to a minimum. In the event the valve stem 26 should break, the valve head 28 will be limited in its downward movement by the webs 18 to prevent entrance of the valve head into the smaller lower end 62 of the valve body 16 or the fluid passageway 64 where it would preclude a continuous flow of drilling fluid through the drill collar 2, valve body 16 and drill bit 4.

When the downward flow of drilling fluid through the passageway 6 is stopped, the valve head 28 will be moved upwardly by the helical spring 32. The tapered area 34 of the valve head 28 will then contact the tapered area 36 of the valve seat 38 to preclude an upward or retrograde flow of the drilling fluid through the drill collar 2 and permit a floating of the drill pipe (not shown). The sealing ring 48 assures an efficient closing of the valve head 28. The valve guide 22 maintains the valve stem 26 in a true vertical position in the valve body 16 to assure efficient operation of the valve head 28.

The float valve 14 also functions as a back pressure valve in the event an unexpected pressure is encountered in the bottom of the well bore during a drilling operation. It will be obvious that if a pressure is unexpectedly developed in the well bore greater than the pressure of the drilling fluid, the valve 28 will be moved upward into a closed position to preclude a retrograde flow of fluid upward through the drill pipe. The unexpected high pressure fluid will then be constrained to flow upwardly through the annulus around the drill pipe, and the surface equipment, such as pumps and the like (not shown), connected to the drill pipe will not be damaged.

Although I have described my novel float valve as being used in a drill collar, it will be apparent to those skilled in the art that a special coupling, such as a float coupling, may be readily designed to receive such a valve. The valve could then be placed at any desired vertical position in the drill string. Therefore, I do not wish to be limited to the use of the valve in a drill collar.

From the foregoing, it is apparent that the present invention will reduce the number of wash outs of drill collars and the like to a minimum. Furthermore, the efficiency of the rotary method of drilling will be increased and the passageway for the drilling fluid will not become plugged in the event the valve stem breaks. In addition, the solid wall valve body, in cooperation with the end and side seals, precludes the drilling fluid from contacting the drill collar after it has entered the float valve.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. In combination with a drill collar having a drill bit secured to the lower end thereof, said drill collar having a fluid passageway therethrough communicating with the fluid passageway of the drill bit and being enlarged adjacent the drill bit to form a downwardly facing annular shoulder above the drill bit, a solid wall tubular body in the enlarged portion of the drill collar fluid passageway, a reciprocable valve in the body, a valve seat in the body for receiving the valve in one position of the valve, and sealing rings protruding from each end of the body and adapted to contact said annular shoulder and said drill bit around the respective fluid passageways.
2. In combination with a drill collar having a drill bit secured to the lower end thereof, said drill collar having a fluid passageway therethrough communicating with the

fluid passageway of the drill bit and being enlarged adjacent the drill bit to form a downwardly facing annular shoulder above the drill bit, a solid wall tubular body in the enlarged portion of the drill collar fluid passageway, the opposite ends of said body being open to form a fluid inlet and a fluid outlet, a reciprocable valve in the body, a valve seat in the body for receiving the valve in one position of the valve, and sealing rings protruding from each end of the body around said inlet and said outlet adapted to contact the annular shoulder and the drill bit. 10

3. In combination with a drill collar having a drill bit secured to the lower end thereof, said drill collar having a fluid passageway therethrough communicating with the fluid passageway of the drill bit and being enlarged adjacent the drill bit to form a downwardly facing annular shoulder above the drill bit, a solid wall tubular body in the enlarged portion of the drill collar fluid passageway, the opposite ends of said body being open to form a fluid inlet at the upper end of the body and a fluid outlet at the lower end of the body, said inlet being substantially 15 20

the same diameter as the drill collar fluid passageway and said outlet being substantially the same diameter as the drill bit fluid passageway, a reciprocable valve in the body, a valve seat in the body for receiving the valve in one position of the valve, and sealing rings protruding from each end of the body around said inlet and said outlet adapted to contact the annular shoulder and the drill bit.
